CLAIM

The ornamental design for a foldable ice tray for food, as shown and described.

DESCRIPTION

FIG. 1 is a front elevational view of a foldable ice tray for food showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a bottom, front and left side perspective view thereof;
FIG. 8 is a top, front and right side perspective view thereof; and,
FIG. 9 is a top, rear and right side perspective view thereof.

1 Claim, 9 Drawing Sheets
